UNITED STATES PATENT OFFICE.

EDWIN BENNETT GILLINDER, OF PORT JERVIS, NEW YORK, ASSIGNOR TO GILLINDER BROTHERS, OF PORT JERVIS, NEW YORK, A COPARTNERSHIP COMPOSED OF WILLIAM T. GILLINDER AND JAMES GILLINDER.

DESIGN FOR A LIGHTING GLOBE.

Application filed May 5, 1922. Serial No. 2,097. Term of patent 7 years.

To all whom it may concern:

Be it known that I, EDWIN BENNETT GILLINDER, a resident of Port Jervis, Orange County, and New York State, and citizen of the United States, have invented a new, original, and ornamental Design for Lighting Globes, of which the following is a specification, reference being had to the accompanying drawing, forming a part thereof, and in which:

Fig. 1 is a side elevation of a lighting globe, showing my new design.

Fig. 2 is a top plan view of the same.

I claim:

The ornamental design for a lighting globe, as shown.

In testimony whereof I hereunto affix my signature.

EDWIN BENNETT GILLINDER.
